INDICIA HOLDER FOR COSMETIC CONTAINERS

Arthur Mainzer, New York, N. Y., assignor to
 Mary Dunhill, Inc., New York, N. Y., a corpora-
 tion of New York

Application June 27, 1940, Serial No. 342,667

2 Claims. (Cl. 40—140)

My invention relates to a holder for monograms, initials, or other indicia for cosmetic containers of the kind typified by lipstick holders in which the lipstick may be retracted and protracted.

The principal object of my invention is to provide a holder construction by means of which initials, monograms or other indicia, hereinafter briefly termed "initials" for purposes of brevity, 10 may be readily inserted and removed.

The modern trend in the sale of cosmetic holders is to provide the purchaser with an article disclosing his or her initials. If these initials were an integral part of the article it is 15 obvious that a very great number of each kind of articles would have to be kept in stock to satisfy the demand. To overcome this feature I have devised a construction by which any desired initials or combination of initials may be quickly 20 and readily inserted in position in the article, thus enabling the seller to carry but a normal stock of the particular article and still be in position to supply a practically unlimited number of initials or monograms.

25 For purposes of simplicity of description I will assume that my invention relates specifically to a lipstick holder although it will be obvious that the invention is equally applicable to a great number of other devices.

30 I accomplish the object of my invention by providing such a lipstick holder with a removable sleeve having orifices through which initials are displayed and in which the initials are securely, yet removably, retained.

35 The invention is illustrated in the accompanying drawing in which

Fig. 1 is a side elevational view of a lipstick holder showing two initials in place;

40 Fig. 2 is a vertical cross-sectional view substantially on the line 2—2 of Fig. 1;

Fig. 3 is a fragmentary vertical sectional view on the line 3—3 of Fig. 1.

45 Fig. 4 is a horizontal sectional view on the line 4—4 of Fig. 2;

Fig. 5 is a detail view, partly broken away, of the cap of the lipstick holder with the initial holding sleeve in place; and

Fig. 6 is an elevation of an initial.

50 Referring to the drawing, 10 denotes the body of a tubular lipstick holder and 11 the neck thereof. The neck and body are bounded by a reenforcing bead 12. The body 10 contains the lipstick and the mechanism for protracting and retracting the same, none of which has been

illustrated inasmuch as it forms no part of the present invention.

The lipstick holder is normally closed by a cap comprising the head portion or dome 13 and the skirt portion 14 which has a friction fit with the 5 external surface of the neck 11. The dome 13 and skirt 14 are connected by a reenforcing bead 15. It will be noted that the neck 11 is of smaller external diameter than the body 10 in order that the skirt 14 of the cap may fit on the neck without undue bulge. The parts so far described, except for the arrangement of the beads are more or less common construction.

The initial holder of my invention comprises a sleeve 16 designed to engage the outer surface 15 of the skirt 14. When the cap is in position on the body of the lipstick holder, i. e., when the lipstick holder is closed, the sleeve is positioned between the beads 12 and 15. This sleeve has a friction fit with the outer surface of the skirt 20 14 and is held securely on the skirt, so that when the lipstick holder is opened by removal of the cap from the body the sleeve remains firmly in position.

I form in the sleeve 16 an orifice or a plural- 25 ity of orifices 17, through which the indicia, as typified by the initial 18 of Fig. 6, may be displayed. The upper and lower edges of the orifice or orifices 17 are bounded by outwardly turned ledges or flanges 19 which constitute seats 30 for the upper and lower edges of the initials 18. This feature is best illustrated in Fig. 3 of the drawing.

It is desirable to divide the orifices 17 into at least two parts by an intermediate bar 20. Al- 35 though two orifices are shown in the drawing for the reception of initials it will be apparent that, without any change in the principle of the invention, a greater or less number of orifices may be provided.

The neck 11 is preferably provided with a spur or projection 21 to aid in retaining the skirt 14 in releasable engagement with the neck, and the skirt 14 somewhere near its upper end is provided with a spur 22 to aid in retaining the 45 sleeve 16 in releasable engagement with the skirt.

It will be understood that the initials 18 are retained in position in the sleeve 16 solely by being seated in the ledges 19 and by their engagement with the external surface of the skirt 50 14.

To insert initials, or to replace positioned initials by others, the cap with the sleeve is removed from the body 10 of the lipstick holder. Thereafter the sleeve 16 is drawn downwardly 55

from the skirt 14. This may be done by either exerting a pull on the sleeve or by holding the sleeve firmly in the fingers and pushing the cap upwardly therefrom. When the lower flange 5 19 has been moved an appropriate distance below the lower edge of the skirt 14 initials, if any, then present in the ledges 19 will drop out and new initials may be inserted by passing such initials upwardly into the orifices therefor, the 10 last part of the inserting motion being accomplished by pushing the sleeve as a whole up until its upper edge strikes the bead 15. If no initials were initially present of course the removal of the initials is unnecessary.

15 To facilitate the insertion and removal of initials the distance between the upper edge 16a of the sleeve 16 and the top of the upper ledge 19 is greater than the distance between the lower edge 16b of the sleeve and the lower 20 edge of the lower ledge 19. By reason of this construction the distance which the initials must originally be inserted is comparatively small so that the amount of manipulation required in inserting the initials is reduced to a minimum 25 thereby enabling even an unskilled operator to insert and remove initials in a very short time.

While I am aware that it has heretofore been proposed to provide a great variety of indicia holders for different kinds of objects, I believe 30 I am the first to provide a construction embodying the orificed sleeve having a frictional fit with a part of the device in which the indicia is to appear and which sleeve is capable of ready application to and removal from a part of the 35 article in order that initials or other indicia may be easily and quickly inserted and exchanged when desired.

To avoid cumbersomeness of expression the

claims will be directed to a lipstick holder but it will be readily understood that holders for other cosmetics and containers of different kinds to which the invention is applicable are deemed to be included in this expression.

I claim:

1. A lipstick holder comprising a body portion having a neck and a cap member comprising a dome and a skirt portion releasably engageable with said neck, the combination therewith of a sleeve frictionally and releasably engageable with the outer surface of said skirt and provided with at least one orifice for the reception of initials, means at the edges of said orifices for supporting said initials and beads carried by the body and cap portions respectively against which opposite edges of said sleeve are adapted to engage when the cap member is in position on the body portion.

2. A lipstick holder comprising a body portion 20 having a neck and a cap member comprising a dome and a skirt releasably engageable with the outer surface of said neck, the combination therewith of a sleeve frictionally and releasably engageable with the outer surface of said skirt 25 and provided with initial receiving orifices, means adjacent the edges of such orifices for supporting said initials in position, there being a greater distance between the upper edge of said orifices and the upper edge of said sleeve 30 than between the lower edge of said orifices and the lower edge of said sleeve, a bead carried by the body member and adapted to be engaged by the lower edge of the sleeve and a bead carried by the cap member and adapted to be engaged by 35 the upper edge of said sleeve.

ARTHUR MAINZER.
